(57) **CLAIM**

The ornamental design for a mobile terminal, as shown and described.

DESCRIPTION

FIG. 1 is a perspective view of a mobile terminal showing the new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a perspective view illustrating a state where a portion of a main body of the mobile terminal is extended to expand the main body and a flexible screen unit of the mobile terminal.

1 Claim, 5 Drawing Sheets
